Attorney.*

UNITED STATES PATENT OFFICE

LOUIS E. ENDSLEY, OF PITTSBURGH, PENNSYLVANIA

TANK-CAR STRUCTURE

Application filed October 8, 1929. Serial No. 398,178.

My invention relates to railway tank car structures, and more particularly to the body portions thereof.

Tank cars are usually of generally cylindrical form, disposed in a horizontal position and having a dome near the central portion thereof. In loading the tank cars, it is the usual practice to completely fill them except, for the space within the dome.

10 The liquid which constitutes the lading of the car is of course non-yielding and when impacts are imposed upon the car, as during transportation or in switching the same, great strains are imposed upon the 15 draft gears. Draft gears are designed so that their springs will be fully depressed when the loaded car is moved at say five miles per hour and the coupler heads are brought into abutting engagement with an- 20 other coupler or other surface. At speeds in excess of the given rate of speed for which the draft gear is designed to absorb impacts, the shocks to the car are very great.

One object of my invention is to provide 25 means whereby a portion of the liquid load of a tank car is deflected and cushioned during compression of the draft gear.

Another object of my invention is to provide means whereby the effective travel of 30 the draft gear will be increased and the gear will not become fully compressed except at speeds materially in excess of those for which the gear is designed in connection with tank cars of former types.

35 One form which my invention may take is shown in the accompanying drawing, wherein the figure is a view of a tank car, partially in side elevation and partially in section.

40 The car frame 2, the draft gears 3 and the car trucks may be of any usual construction, the draft rigging being of course of the usual spring and friction type that is yield- 45 able or compressible to varying degrees at various loads. The draft gears are of course designed to have a buffering capacity dependent upon the weight of the car and length. For example, they may be so designed that 50 their springs are fully compressed only when

brought into play to resist movement of a car at say five miles per hour.

The car body or tank 4 may be made in any well-known manner, but instead of being provided with a centrally-disposed dome, contains two domes 5 and 6. The domes may be of any suitable diameter, depending upon the extent to which it is desired to relieve the draft gears of shocks. For example, if the diameter of the tank 4 55 be eighty inches, the domes could each suitably be forty inches in diameter.

The domes 5 and 6 are preferably normally air-tight, except that the dome 6 may be provided with the usual relief valve to 60 permit escape of gases and with a cover or closure permitting access thereto for the purpose of filling the car.

My invention is particularly directed in the arrangement of domes 5 and 6. As 70 these domes are above the liquid level, it will be seen that if a pulling force is exerted upon the draft gear at the right hand end of the car or a pushing force exerted upon the draft gear at the left hand end of 75 the car, there will be an end thrust imposed upon the left hand end of the car through inertia of the liquid contents thereof.

In tank cars of the usual type, the liquid being incompressible, the shock to the draft gear would be the same as though the car body 4 were filled with a solid. However, by my arrangement, the liquid is permitted to become somewhat displaced, since a portion thereof adjacent to the left hand end 85 of the car will be deflected upwardly into the dome 6, thus allowing for movement of substantially the entire body of liquid within the tank. Yielding resistance is offered to this upward movement both by the head 90 pressure within the dome 6 and by the air cushion developed therein, through rise of the liquid.

The degree of cushioning under given conditions of operation will depend largely upon the diameter of the dome 6 with relation to the diameter of the tank 4. Thus, if the dome 6 be made of greater diameter than shown in the drawing, a still larger amount of liquid 100

could be displaced, thereby still further relieving the draft gears of shocks.

Assuming the dome 6 to be forty inches in diameter and the tank body eighty inches in diameter, the liquid load within the tank may shift 4 inches or in other words may shift one quarter of the distance which the liquid rises in the dome 6. That is, if the liquid rises in the dome 6, for a distance of sixteen inches, the main body of liquid will be displaced for a distance of approximately four inches.

By the use of my invention, a draft gear which is ordinarily designed to be fully compressed when the car is subjected to impacts at switching speeds of five miles per hour will not become fully compressed except at speeds of perhaps seven miles an hour, depending upon the relative sizes of the domes 20 and the car body.

My invention has the further advantage that the internal stresses within the car body arising through surging or pounding of the liquid when the car is subjected to impacts are reduced by reason of the relief afforded through use of the domes, as above-explained. Tank cars as at present constructed are frequently caused to leak through fluid pressures developed therein upon impacts of the 30 car.

The cushioning effect resulting from location of the dome 6 is duplicated by the use of the dome 5, when shocks are imparted to the car in a direction opposite to that above described in connection with the discussion of the dome 6.

If the domes are twenty inches in height, and liquid rises therein for a distance of sixteen inches as above-suggested, the air will be compressed to an extent that it will have a pressure of approximately seventy pounds per square inch upon the liquid, assuming of course that the domes are air-tight, so that not only is shock absorbed through vertical 40 rise of the liquid in the domes, but a yielding resistance is offered by the entrapped air.

I claim as my invention:

1. Railway car structure comprising an underframe and a tank body of elongated 50 form mounted on said frame and disposed longitudinally thereof, a chamber communicating with the said body and positioned to permit displacement of substantially the entire liquid content under end thrust imposed 55 upon the said body, and to receive a portion of the liquid so displaced.

2. A vehicle having a tank-like body of elongated form disposed in parallelism with 60 the line of movement of the vehicle, and a chamber for confining air and for utilizing the said air to cushion movement of liquid within the said body, the said chamber communicating with the interior of said body 65 and being of sufficient area to permit dis-

placement of such quantity of liquid lading as to materially dampen buffing forces.

3. A vehicle having a tank-like body of elongated form disposed in parallelism with the line of movement of the vehicle, and a dome extending upwardly from a point adjacent to each end of the said body, the said domes having communication with the interior of the body and each of an area to permit displacement of such quantities of liquid lading as to materially dampen buffing forces.

4. A vehicle having a tank-like body of elongated form disposed in parallelism with the line of movement of the vehicle, and a dome extending upwardly from a point adjacent to each end of the said body, the said domes having unrestricted communication with the interior of the body and each of an area to permit displacement of such quantities of liquid lading as to materially dampen buffing forces.

In testimony whereof I, the said LOUIS E ENDSLEY have hereunto set my hand.

LOUIS E. ENDSLEY.
